UNITED STATES PATENT OFFICE

2,525,764

SAFETY WINCH

Jesse M. Benson, Concord, Tenn., assignor to
Sasgen Derrick Co., Chicago, Ill., a corporation
of Illinois

Application May 28, 1946, Serial No. 672,781

4 Claims. (Cl. 254—186)

1

This invention relates to winches and is an improvement over the construction embodied in my prior patents, No. 2,083,489, dated June 8, 1937, and No. 2,243,789, dated May 27, 1941, for Winches.

An object of this invention is to provide an improved winch embodying a safety brake construction which will automatically lock the winding drum against unwinding if the winding crank should be released.

Another object of this invention is to provide a winch of this type which is so constructed that the torque caused by the unwinding of the drum will not be communicated directly to the winding crank.

A further object of this invention is to provide a winch of this type wherein the locking or braking means for the winding drum will be constantly urged to locking or braking position when the drum is turning to unwind the cable therefrom, and the winding crank during the unwinding operation operates to move the locking or braking means to released position by reverse rotation of the crank.

A further object of this invention is to provide an improved winch of the automatically braking type which also includes means whereby the automatic braking means may be disengaged and the unwinding of the drum controlled by a hand operated brake of conventional construction.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail side elevation of a winch constructed according to an embodiment of this invention.

Figure 2 is a sectional view taken either on line 2—2 of Figure 1 or line 2—2 of Figure 3.

Figure 3 is a sectional view taken on the line 3—3 of Figure 2.

Figure 4 is a sectional view taken on the line 4—4 of Figure 3.

Figure 5 is a fragmentary sectional view taken on the line 5—5 of Figure 2.

Figure 6 is a fragmentary sectional view taken on the line 6—6 of Figure 1.

Referring to the drawings, the numeral 10 designates a stationary horizontal shaft which is

2

secured at one end in a bushing 11 carried by a standard 12. The opposite end of the shaft 10 is secured by means of a fastening member 13 in a bushing 14 carried by a gear housing generally designated as 15. A winding drum 16 is rotatably mounted on shaft 10 and includes a cylindrical body 17, having an annular flange or end wall 18 at one end thereof, and a bearing boss or bushing 19 extending interiorly of cylindrical body 17. The drum 16 also includes an opposite end wall 20, and a second bearing boss or bushing 21 extends inwardly from end wall 20 and interiorly of cylindrical body 17. The body 17 has removably mounted therein a threaded plug 22, by means of which a lubricant may be discharged interiorly of the body 17 for maintaining constant lubrication of the bearings 19 and 21. The standard 12 is held in spaced apart relation with respect to the housing 15 by means of a pair of tubular spacing members 22 and 23, which engage about bolts 24 and 25, respectively.

End wall 20 of drum 16 has formed integral therewith an annular flange or brake drum 26 extending in the direction of gear housing 15, and the interior of flange 26 is formed with gear teeth 27. A brake band 28, having a braking element 29 secured to the inner side thereof, is disposed about the brake drum 26, being secured at one end to fastening member 24 and the opposite end of band is secured as at 29a to an eccentric 30, which is rockably carried by the fastening member 25. The free end of band 28 is reverted or bent upon itself to form an eye 31, and the eye 31 is split as indicated at 32 for receiving the eccentric 30. Eccentric 30 has fixed thereto a brake operating lever 33, which extends upwardly and is adapted to be rocked outwardly, or to the left, as viewed in Figures 4 and 6, to bring the braking member 29 into braking position against the periphery of brake drum or flange 26. This braking means provides a conventional hand operated braking means whereby drum 16 may be braked in its unwinding operation independent of the automatic locking means to be hereinafter described.

Housing 15 comprises an outer wall 34 formed of a substantially circular flange 35 and an inner wall 36 secured to the flange 35 by fastening members 37. The inner wall 36 includes an inwardly projecting arcuate wall 38 extending interiorly of brake drum 26 and a wall 39 is carried by arcuate wall 38, and is positioned parallel to the inner wall or flange 20 of drum 16. An idling gear or pinion 40 is rotatably carried by a shaft 41, engaging through walls 36 and 39 and is adapted

to mesh with the internal gear 27 formed in the braking drum 26. A sun gear 42 is rotatably carried by stationary shaft 10, and is adapted to mesh with intermediate or idling gear 40. Sun gear 42 has formed integral therewith a hub 43, which is formed with exterior threads 44. A gear 45 having internal threads 46 is threadably mounted on threads 44 of hub 43 and constitutes a high ratio gear for rotating sun gear 42. A large gear 47, including a web 48, is welded to, or otherwise fixedly secured to, gear 45 and the web 48 constitutes one element of a braking means as will be hereinafter described.

Hub 43 at its inner end has formed integral therewith a plate 49 constituting another element of a braking means which is rotatable with gear 42. A braking plate 50 is loosely mounted on the inner end of hub 43, being interposed between plate or web 48 and plate 49. The opposite faces of plate 50 have secured thereto braking means 51 and 52, so as to provide the necessary friction for holding plates 48 and 49 against rotation. The outer margin of plate 50 is formed with ratchet teeth 53 with which a spring pressed dog 54, carried by a shaft 55, is adapted to engage. Dog 54 is adapted to normally hold plate 50 against rotation in an unwinding direction while permitting free rotation of this plate in a direction to wind a cable or other flexible member on drum 16. Dog 54 includes a handle 56, having a laterally projecting lug 57 formed integral therewith and one end of a spring 58 engages lug 57 and the other end of spring 58 is fixed to the wall 36, being positioned to normally hold dog 54 in either ratchet engaging or in released position.

A second dog 59 is rockably mounted on shaft 55 and is adapted to engage the teeth of low speed gear 47. Dog 59 is constructed similar to dog 54 and includes a handle 60, having a laterally projecting lug 61 with which one end of a spring 62 is connected. The other end of spring 62 is connected to an eye 63 carried by the front or outer wall 36 of housing 15. Spring 62 is adapted to hold dog 59 in either engaging or released position, and is so positioned as to permit free rotation of gear 47 in a drum winding position, while holding drum 16 against rotation in an unwinding direction.

In order to provide for rotation of drum 16 to wind a cable thereon, I have provided a driving gear 64 which is carried by a removable stub shaft 65. Housing 15 is formed with a pair of cylindrical bushings 66 and 67 in a selected one of which shaft 65 is adapted to be positioned. Bushing 66 is positioned innermost for holding shaft 65 so that gear 64 will engage with gear 45, whereas bushing 67 is positioned for holding shaft 65 so that gear 64 will engage the teeth of gear 47. Shaft 65 is releasably locked in either bushing 66 or 67 by means of a locking pin 68, which loosely engages through bushings 66 and 67, and is formed at its outer end with a handle 69. Shaft 65 is formed with a peripheral groove 70 within which pin 68 is adapted to engage, and pin 68 is formed with a pair of arcuate cutouts 71 and 72, so that when handle 69 is raised upwardly the two cutouts 71 and 72 will be lowermost and shaft 65 may be withdrawn from either one of the bushings.

Shaft 65 at its outer end is formed with a head 73 which is larger in diameter than the diameter of shaft 65, so that head 73 will substantially bear against the outer end of either bushing 66 or 67. Head 73 is formed with a diametri-

cal opening 74 through which a lever 75 loosely engages, and lever 75 is secured in adjusted position with respect to head 73 by means of a set screw 76. One end of lever 75 has a right angularly disposed crank handle 77 secured thereto so that shaft 65 may be manually rotated. The provision of set screw 76 and the adjustable mounting of lever 75 in head 73 provides a means whereby the leverage for rotating shaft 65 may be adjusted within the limits of the length of lever or bar 75.

In order to provide means for limiting the outward movement of gear 45 on hub 43, a collar 78 is threaded onto hub 43 and engages in a recess 79 formed in an offset hub member or bushing 80 carried by end wall 34. Collar 78 is adapted to be locked on hub 43 by means of a set screw 81.

In the use and operation of this winch shaft 65 may be inserted in either bushing 66 or 67. As disclosed in Figure 2, shaft 65 is locked in bushing 66 and engages high speed gear 45. As shaft 65 is rotated in a clockwise direction, drum 16 will be rotated through the gear train to wind the cable thereabout. As gear 45 is rotated by gear 64, gear 45 will partly rotate on hub 43 in an unthreading direction and will bear against fixed collar 78. With gear 45 bearing against collar 78 brake element 48 will be disposed in spaced relation with respect to braking plate 50 which is loose on hub 43. At the time gear 45 is rotated in a counterclockwise direction with gear 64 rotating clockwise, dog 59 will ride over the outer teeth of gear 47. Inasmuch as clutch plate or web 48 is disengaged from clutch plate 50, the clutch formed by the plates 48, 49 and 50 will be disengaged.

In the event that the torque on drum 16 should cause rotation of this drum in an unwinding direction, gear 42 will be rotated in a clockwise direction, and as gear 47 is held against rotation in a clockwise direction by dog 58, gear 45 will be threaded inwardly or forwardly on hub 43 so as to bring clutch plate 48 into engagement with plate 50, and the latter will engage clutch plate 49, which is fixed with respect to gear 42. Drum 16 will thereby be locked against reverse or unwinding rotation and the torque or force of the unwinding rotation will be disconnected from shaft 65 and crank handle 77. It will, therefore, be apparent that if crank handle 77 should suddenly be released during the winding operation, drum 16 would immediately become locked against unwinding.

In order to permit the unwinding of drum 16, it is necessary that shaft 65 be rotated in a counterclockwise direction at a speed sufficient to move gear 45 to the right, as viewed in Figure 3, and maintain clutch plate 48 in disengaged position. This reverse rotation of shaft 65 is effected without any of the torque or force of drum 16 being communicated to the crank, so that this crank may be freely rotated in a reverse direction at the desired speed in order to control the reverse or unwinding rotation of drum 16.

If it is desired to permit free rotation of drum 16 in an unwinding direction, dogs 54 and 55 may be rocked upwardly to their released position, and crank 77 may then be used to regulate the reverse rotation of the drum. Shaft 65 may be inserted in either bushing 66 or 67 depending on the desired speed of rotation of drum 16, which is to be effected by rotation of drive shaft 65.

This improved winch provides a safety factor

through the automatically operated clutch which will automatically prevent unwinding rotation of drum 16, and the winch embodies an exceedingly compact gear and clutch construction which will permit of a strong winch being provided in a relatively small size. It will, of course, be understood that this winch may be made in any desired size, but the gear and clutch construction is such as not to unduly increase the size of the structure.

What I claim is:

1. A winch comprising a stationary shaft, a winding drum rotatable on said shaft, a gear housing secured to one end of said shaft, a ring gear fixed relative to said drum, a sun gear rotatable on said shaft, an intermediate gear rotatably carried by said housing and meshing with said sun and ring gears, a threaded hub fixedly carried by said sun gear, a high speed gear threadably engaging said hub, a brake plate carried by said sun gear, a second brake plate carried by said high speed gear, an intermediate brake member rotatably carried by said hub and disposed between said first and second brake plates, peripheral teeth carried by said intermediate brake plate, a pivoted pawl engaging said teeth for holding said intermediate plate against rotation in a drum unwinding direction, a low speed gear carried by said second brake plate, a driving gear, and means carried by said housing supporting said driving gear for selective engagement with said high and low speed gears.

2. A winch as set forth in claim 1 including a manually operable brake band encircling said ring gear.

25

30

35

3. A winch as set forth in claim 1 including a pivoted pawl carried by said housing engageable with said low speed gear to hold said low and high speed gears against reverse rotation.

4. A winch comprising a stationary shaft, a winding drum rotatable on said shaft, a gear housing secured to one end of said shaft, a ring gear fixed on said drum, a sun gear rotatable on said shaft, a geared connection between said ring and said sun gear, a threaded hub on said sun gear, a brake plate on said hub, a high speed gear threadably engaging said hub, a brake plate carried by said high speed gear, an intermediate gear having braking surfaces thereon rotatable about said hub between said first and second brake plates, means engaging said intermediate gear for holding said intermediate gear against rotation in a drum unwinding direction, and means for rotating said high speed gear about said shaft whereby said drum will not unwind at a speed greater than the speed of the high speed gear in a drum unwinding direction.

JESSE M. BENSON.
